W. J. FAWVER,
CLOCK ESCAPEMENT,
APPLICATION FILED DEC. 31, 1921.

1,423,410.

Patented July 18, 1922.

UNITED STATES PATENT OFFICE.

WILLIAM J. FAWVER, OF PATESVILLE, KENTUCKY.

CLOCK ESCAPEMENT.

1,423,410.

Specification of Letters Patent. Patented July 18, 1922.

Application filed December 31, 1921. Serial No. 526,312.

To all whom it may concern:

Be it known that I, WILLIAM J. FAWVER, a citizen of the United States, residing at Patesville, in the county of Hancock and 5 State of Kentucky, have invented new and useful Improvements in Clock Escapements, and of which the following is a specification.

This invention relates to clocks, particularly to those of the pendulum type, and has 10 for its object the provision of a novel escapement which is of peculiar construction whereby the pendulum may be always maintained in position so as to insure proper running of the clock even though the supporting 15 shelf, table or other device or article upon which the clock is disposed may be extremely uneven so that the clock does not set level.

An important and more specific object is 20 the provision of a novel spring clutch device forming part of the mechanism whereby when the pendulum is given a somewhat more violent swing than usual the clutch device will be automatically released temporarily to permit the parts to adjust themselves, the arrangement being such that when 25 the pendulum reduces its speed to normal the clutch will again grip and have its holding action for insuring operation of the escapement.

30 An additional object is the provision of a mechanism of this character which will be simple and inexpensive in manufacture and installation, highly efficient in use, positive in action, durable in service and a general 35 improvement in the art.

With the above and other objects and advantages in view, the invention consists in the details of construction to be hereinafter more fully described and claimed, and illustrated in the accompanying drawings in 40 which,

Figure 1 is an elevation of a clock mechanism showing my device associated therewith.

45 Figure 2 is an enlarged elevation of the essential parts of my device.

Figure 3 is a cross-sectional view through the drum and spring clutch and,

Figure 4 is a detailed view.

50 Referring more particularly to the drawings the letter A designates a portion of a clock mechanism including the usual escapement wheel B with which is associated the usual verge which naturally has associated therewith a pendulum E which is suspended 55 in the usual manner.

In carrying out my invention I make use of novel connecting spring clutch mechanism to be hereinafter described. This clutch mechanism comprises a drum 10 which is of frusto-conical formation and which is formed with an outwardly extending peripheral flange 11 with which is connected the verge wire 12 which has a laterally extending insert terminating in a hook 14 which engages the pendulum suspension means E.

Encircling the drum 10 is a split spring ring 15 which is formed at one portion with an extension 16 connected with the verge C as indicated at 17. Opposite the extension 16 the ring 15 is split as shown and is formed with two lugs 18 which are pivotally connected at 19 with the inner corners 20 of a pair of peculiarly shaped levers 21 which have their adjacent edges formed with inclined extensions 22 which normally contact, and which have their lower ends formed with laterally directed extensions 23.

Suitably mounted upon the clock movement or frame are banking pins 24 which are adjustable and which are angular in shape. The upper ends of these banking pins are provided with studs 25 which are engageable by the levers 21 as will be hereinafter explained. The pendulum suspension means E is connected with one of the banking pins as indicated at 26.

Assuming that the clock has been provided with the above described mechanism, the operation is as follows;

The spring clutch 15 fits upon the drum 10 and is friction tight. The other parts of the mechanism are arranged as above described and as clearly illustrated in the drawings. When the clock is placed upon any shelf, if the clock does not have the proper position, that is to say if it is not level and consequently will not run, it is merely necessary that the operator give the pendulum B a good swing, that is to say a swing of greater violence than occurs during the ordinary running of the clock. When this is done the levers 21 will strike against the studs 25 on the banking pins 24, thereby causing the spring ring 15 to release its grip on the drum 10 sufficiently that the drum may conform to the position by the pendulum rod E. The studs 25 are set far enough out on each side so that the levers 21 don't strike them when the clock resumes its normal pendulum action. As

soon as the parts automatically adjust themselves it is of course apparent that the spring ring 15 will again grip the drum 10 and maintain the proper adjustment while the clock is in operation.

From the foregoing description and a study of the drawings it will be apparent that I have thus provided a novel escapement mechanism, that is to say a pendulum 10 mounting in association with an escapement of a clock whereby the clock may be made to run properly regardless of whether it be standing upon a level shelf or other support or upon an uneven support. The action of adjustment is entirely automatic and is accomplished merely by giving the pendulum bar an unusually hard swing so as to cause the automatic release and subsequent regripping of the spring clutch mechanism. 15 Owing to the simplicity of the construction it is believed that there is very little to get out of order and that the device should consequently have a long life and efficiently perform all the functions for which 20 it is intended.

While I have shown and described the preferred embodiment of the invention, it is of course to be readily understood that I reserve the right to make such changes in the 30 form, construction and arrangement of parts as will not depart from the spirit of the invention or the scope of the subjoined claims.

Having thus described my invention I 35 claim:

1. In combination with a pendulum, an escapement wheel and a verge associated with the latter, a clutch mechanism between

the pendulum rod and the verge comprising 40 a drum, a split ring frictionally engaging about the drum and connected with the verge, a pair of levers connected with the split ring at opposite sides of the split therein and having their inner edges formed with normally engaging projections, the 45 lower ends of said levers being formed with outward projections, a pair of banking pins mounted upon the clock frame and carrying studs engageable by said levers, said pendulum rod being associated with the verge and 50 verge wire.

2. In combination with an escapement wheel, verge associated therewith and the pendulum of a clock mechanism; an automatically self adjusting clutch mechanism 55 between the pendulum and the verge comprising a drum of substantially frusto-conical formation carrying a peripheral flange, a verge wire connected with said flange terminating in a hook, a split ring frictionally encircling the drum and formed with an extension connected with the verge, said ring being formed with lugs at opposite sides of the split, a pair of levers pivotally connected with said lugs and having their 60 confronting edges formed with engaging projections, said levers having laterally extending lower ends, a pair of banking pins mounted upon the movement frame and carrying studs engageable by the lateral extensions of the levers, the suspension means of the pendulum being associated with the 65 verge and verge wire.

In testimony whereof I affix my signature.

WILLIAM J. FAWVER.
